Fig. 4.

A diagram illustrating a helical structure, likely a protein-DNA complex. The structure is composed of several subunits, each represented by a circle with a smaller circle inside, and connected by lines. A large circle on the left is labeled 'A'. To its right is a subunit labeled 'B' with an arrow pointing to the right. Further to the right is a subunit labeled 'C' with a curved arrow pointing upwards and to the right. Below the subunit 'C' is a label '6'. The entire structure is labeled with a large number '4' in the top left corner.

UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

WATER EXHAUST BOX.

Application filed May 16, 1923. Serial No. 639,439.

To all whom it may concern:

Be it known that I, ALBERT R. THOMPSON, a citizen of the United States, residing at San Jose, in the county of Santa Clara and State of California, have invented certain new and useful Improvements in Water Exhaust Boxes, of which the following is a specification.

My invention relates to those machines used in the canning art, which from their function of partially expelling the air content from the filled and still open containers, are known as exhaust-boxes. In these machines a continuous procession of cans moves through a heated chamber in a path of sufficient length to subject the goods for the time required for the "first cook," as the exhaust process is usually called; and in order to make this extensive path consistent with economy in floor space it is usual to direct it in various forms of tortuous or to and fro courses throughout a relatively spacious chamber.

The heat for the box is generally supplied by steam either admitted directly or as a means for heating the air; but in some machines which are found for various reasons to have special advantages, the heating medium is water the temperature of which is derived from any suitable source, as, for example, steam coils. Such machines are termed water exhaust-boxes, and in them the cans are immersed in the hot water to a predetermined depth and carried through the water at that depth.

My present invention concerns this water type of exhaust-box. Its object is to provide means for the entrance of the can procession to the required depth of immersion in the heated water, and its delivery therefrom, said means being in such relation to the extensive path through which the procession passes, that they do not materially detract from the extent of said path, nor from the maximum capacity of the box consistent with minimum floor space.

To this end my invention consists in the novel water exhaust box which I shall now fully describe by reference to the accompanying drawings, in which—

Fig. 1 is a top plan view of my box the cover being removed.

Fig. 2 is a longitudinal vertical section of the box, taken on the line 2—2 of Fig. 1.

Fig. 3 is a cross section, on the line 3—3

of Fig. 2, the disks of the entrance and delivery sections of the conveyer being omitted.

Fig. 4 is a top plan, broken, showing a modification of the box with respect to the location of the entrance and the delivery sections of the can path.

Fig. 5 is a section on the line 5—5 of Fig. 4.

Before describing the drawings in detail it must be understood that my invention is not in its broad sense confined to any particular form or type of conveyer which carries the can procession through its path. Such conveyers are of many kinds. The form I have herein shown for the sake of illustration is a common one, and is known as the disk-type of conveyer. It comprises a plurality of revoluble juxtaposed disks, with overlying directional guides by which the cans resting on the disks are moved to and over successive disks from their entrance to the box to their discharge. This type of conveyer, I have, however, found to be specially applicable to my present invention in that while giving a maximum can capacity consistent with floor space, it lends itself admirably to the economic can entrance and discharge, which I seek to attain.

1 is the tank or shell of the exhaust box having a can-inlet at 2 and a can-outlet at 3, as shown in Fig. 1.

In the tank is contained a body of heated water, the level of which is indicated by w—w in Fig. 2 and in Fig. 3. Referring to Fig. 1, it will be seen that the box is substantially filled to its capacity with the main body of the conveyer disks 4 arranged in the parallel rows A, B, C, each row being preferably a double line, with the directional guides 5 adapted to lead the cans from one disk in one line of the row to the next disk in the other line of said row and back to the next disk in the first line and so on. At the end of each double line row, are transfer disks 6 connecting the rows. Thus in the box and filling practically its capacity, the can path, as seen in Fig. 1, leads from the right hand end of double line row A, over said row to its left hand end, thence over the transfer disks 6 to the left hand end of row B, and to the right over said row and thence back to the left over row C. All these disks are in the same horizontal plane, and are far

enough below the level $w-w$ of the water, as seen in Fig. 3, to cause the cans supported upon them to be submerged in the water to a predetermined depth, the open tops of the cans being above the water level, as is shown by the can designated by 7 at the left hand end of Fig. 2.

The entrance section of the can path leads from the inlet opening 2 of the box, Fig. 1. It consists preferably of the single line row of disks 8 with their directional guides 9. If the box is a short one, this entrance section may incline downwardly for the full length of the box to its terminal where it joins by means of the transfer disks 10 the first double line row A of the main portion of the can path, whereby sufficient length is provided to make the down grade at a small enough angle to avoid any spilling of the can contents; but when the box is a longer one, the grade of the entrance section may safely terminate at about the transverse middle of the box, where it reaches the level of the main path disks 4, as seen in Fig. 2, and its remaining portion then continues at this level.

The arrangement of the delivery section of the can path is opposite to that of the entrance section. As shown in Fig. 1, the delivery section is preferably a single line row of disks 11 with directional guides 12, which joins by means of the transfer disks 13 the double line row C of the main portion of the can path at the left hand end, and thence continues to the right on the same level as the disks of row C, to the transverse middle of the box, from which point, as shown in Fig. 2, it proceeds on an up-grade to the outlet 3 of the box.

It will now be seen that a can entering the box at inlet 2, Fig. 1, will pass down over the inclined disks 8 to the cross median line of the box, as in Fig. 2, at which point it will be submerged in the hot water to the predetermined depth. Thence it will travel at said depth to the first double line row A, and at the same depth will advance through the water back and forth successively over rows A, B and C, and then enter on the delivery disks 11. On these at the same depth it will advance to the middle of the box and from there will gradually rise to the outlet 3.

In Fig. 3 I have indicated an overhead drive for the conveyer disks of substantially the nature of the underlying drive common in this type of disk exhaust boxes, the change from below to above being desirable, since the tank contains water, which might otherwise be subjected to leakage.

This driving mechanism comprises the power shaft 14 with its bevel pinions 15, the vertical shafts 16 with their bevel gears 17 and pinions 18 the latter meshing with the gears 19 of the disks.

In Figs. 1, 2 and 3, thus far described, the entrance and delivery sections of the can conveyer or path are shown at the sides of the box. This, however, is not essential, for as shown in Figs. 4 and 5, they may be disposed at the ends of the box. In these Figs. 4 and 5, the parts being identical, are designated by similar numerals but what has been previously said about the entrance and delivery sections possibly extending for their full length on a gradient when the distance is relatively short, is here well illustrated, said sections being shown in Fig. 5 on an incline for their full length, since the ends of the box are short.

It will now be seen that in a water exhaust box, such as herein described, there is an extensive can path filling the treating chamber to its capacity, the inleading and outleading sections of the path forming an intimate part thereof, but so disposed as to occupy the least space, and by leading the cans into and out of the water in a minimum of distance and time said sections perform their function without detracting from the necessary function of the main body of the path with respect to time of treatment, length of path and size of box.

I claim:

A water exhaust-box comprising a hot-water-containing tank having a can inlet and a can outlet both above the level of the water; a main can-conveyer within the box and substantially filling its capacity, said conveyer consisting of revolute juxtaposed disks with overlying directional guides, and arranged in a plurality of end connected rows, to carry the cans in a to and fro course through the water; an entrance can-conveyer within the tank disposed on one border of the main conveyer and consisting of revolute, juxtaposed disks with directional guides, said entrance conveyer leading from the tank inlet on a down grade to the level of and joining one end of the main conveyer; and a delivery conveyer within the tank consisting of revolute juxtaposed disks with directional guides, said conveyer joining the other end of the main conveyer and leading along the opposite border of said main conveyer on an up grade to the tank outlet.

In testimony whereof I have signed my name to this specification.

ALBERT R. THOMPSON.
